UNITED STATES PATENT OFFICE.

WILLIAM HENRY KELSO, OF BUTTE, MONTANA.

MINER'S PICK.

SPECIFICATION forming part of Letters Patent No. 588,339, dated August 17, 1897.

Application filed February 19, 1897. Serial No. 624,254. (No model.)

To all whom it may concern:

Be it known that I, WILLIAM HENRY KELSO, a citizen of the United States, residing at Butte, in the county of Silver Bow and State of Montana, have invented certain new and useful Improvements in Miners' Picks; and I do declare the following to be a full, clear, and exact description of the invention, such as will enable others skilled in the art to which it appertains to make and use the same.

My invention has relation to improvements in miners' picks; and the object is to provide the pick with a detachable point.

To this end the novelty consists in the construction, combination, and arrangement of the same, as will be hereinafter more fully described, and particularly pointed out in the claim.

In the accompanying drawings the same reference-characters indicate the same parts of the invention.

Figure 1 is a perspective view of my improved mining-pick. Fig. 2 is a longitudinal section of one of the arms and point, and Fig. 3 is a horizontal section of the same.

1 represents the eye, and 2 the integral arms. The outer ends of these arms are each formed with a longitudinal rectangular socket 3, the side walls 4 of which are parallel to each other, while the top and bottom walls 5 gradually converge from the shoulder 6 inwardly toward the eye.

7 represents a circular orifice extending through the top and bottom walls.

9 represents the detachable point, and it is provided with an integral rectangular shank

10, formed with a shoulder 12 and parallel sides 13 and 14, while the top and bottom sides 15 and 16 converge from the shoulder to the end of the shank. The shank itself conforms exactly in shape to the socket 3, which it snugly fits.

An orifice 17 in the shank 10 is slightly curved longitudinally and out of alinement with the corresponding orifice in the socket, 45 so that when the pin 18 is inserted it bends to conform to the curved orifice 17, forming a kink and making it impossible for its accidental withdrawal.

Having thus described my invention, what I claim as new and useful, and desire to secure by Letters Patent of the United States, is—

A miner's pick comprising the eye 1, the integral arm 2 formed with the socket 3 having orifices 7, in combination with the detachable point 9 having the integral shank 10 provided with the longitudinally-curved orifice 17 and the pin 18, whereby when the shank 10 is inserted in said socket and its inner end 60 abutting against the end wall thereof and the pin driven through the orifices 7 and 17, a portion of the said pin will be bent or knocked out of alinement with the orifices 7, substantially as set forth.

In testimony whereof I hereunto affix my signature in presence of two witnesses.

WILLIAM HENRY KELSO.
